CLAIM

The ornamental design for an automotive vehicle body, toy vehicle body replica and/or other replica, as shown and described.

DESCRIPTION

FIG. 1 is a top, front and side perspective view of an automotive vehicle body, toy vehicle body replica and/or other replica showing our new design;

FIG. 2 is a top, rear and side perspective view thereof;

FIG. 3 is a side elevational view thereof;

FIG. 4 is a top plan view thereof;

FIG. 5 is a front elevational view thereof;

FIG. 6 is a rear elevational view thereof;

FIG. 7 is an opposite side elevational view thereof;

FIG. 8 is a bottom plan view thereof;

FIG. 9 is an enlarged fragmentary front elevational view thereof, taken along line 9-9 in FIG. 5;

FIG. 10 is an enlarged fragmentary rear elevational view thereof, taken along line 10-10 in FIG. 6; and,

FIG. 11 is an enlarged fragmentary side elevational view thereof, taken along line 11-11 in FIG. 7.

The portions of the automotive vehicle and the trademark “LUCID” shown in broken lines throughout the drawing views are for illustrative and environmental purposes and form no part of the claimed design.

1 Claim, 10 Drawing Sheets
